C. E. ANDERSON

HINGE

Filed Nov. 29, 1922

UNITED STATES PATENT OFFICE.

CARL ERIC ANDERSON, OF GRAND HAVEN, MICHIGAN, ASSIGNOR TO GRAND HAVEN STAMPED PRODUCTS COMPANY, OF GRAND HAVEN, MICHIGAN, A CORPORATION OF MICHIGAN.

HINGE.

Application filed November 29, 1922. Serial No. 603,949.

This invention relates to improvements in hinges and its purpose is to provide a device which may be readily applied and which is adapted to maintain a firm support for the 5 movable part which is supported by the hinge.

The principal object of the invention is to provide an improved form of hinge particularly adapted for use in connecting the 10 doors to the bodies of automobiles. A further object is to provide a hinge which may be applied to the supporting member without the necessity of using a chisel or other such tool in forming a recess to receive the 15 hinge.

Still another object is to provide a hinge in which the parts may be economically manufactured and readily assembled.

These and other objects and advantages of 20 the invention will appear more clearly from the following specification taken in connection with the accompanying drawings in which one embodiment is illustrated. In the drawings, Fig. 1 shows a partial side 25 elevation of an automobile body to which the improved hinge is applied. Fig. 2 shows an enlarged horizontal section taken on the line 2—2 of Fig. 1, looking in the direction of the arrows. Fig. 3 shows a vertical section taken on the line 3—3 of Fig. 2 looking 30 in the direction of the arrows. Fig. 4 shows a transverse vertical section taken on the line 4—4 of Fig. 2, looking in the direction of the arrows. Fig. 5 shows a transverse section taken on the line 5—5 of Fig. 2 looking 35 in the direction of the arrows. Fig. 6 shows a perspective view of the bracket which is adapted to be mounted in the cylindrical member carried by the body of the 40 car, and Fig. 7 shows a perspective view of the bracket which is adapted to be secured to the door of the car.

Although the improved hinge of the present invention is capable of various uses, it 45 has been illustrated in connection with the door 10 of an automobile body 11. As usually constructed the automobile body has an upright wooden frame member 12 along the edge of the door opening and the usual 50 sheet metal covering 13 is applied to the outer side of this frame member. The door 10 is similarly provided with an upright wooden frame member 14 having a sheet metal covering 15 applied to the outer side

thereof and arranged to project over the 55 gap 16 which is usually provided between the edge of the door and the frame of the door opening to prevent the binding of the door after long continued use of the automobile. These parts are the usual construction and are illustrated for the purpose of 60 explaining the application thereto of the improved hinge which constitutes the present invention.

The hinge comprises a cylindrical cup-shaped supporting member 20 having a bottom or end wall 21 and an outer transverse flange 22. The outer edge 22^a of this flange is circular in contour, being concentric with the walls of the cylindrical member 20, but 70 the lateral sides thereof are cut away and shown at 22^b and 22^c so that the plate 22 may be fitted on the end of wooden frame member 12 without overlapping the lateral edges thereof. This supporting member is 75 adapted to seat in a cylindrical recess 23 which is formed in frame member 12, preferably by means of an auger which may be adjusted to bore a hole of substantially the same diameter as the cup-shaped member 20 80 so that this member may be put in place with a drive fit adapted to prevent vibration of the hinge in its support regardless of the strains to which it is subjected in practice. Before boring the hole 23 to receive the 85 member 20, the auger may be adjusted to bore a hole of larger diameter in order to form a recess 24 to receive the plate 22, the plate 22 being located with its outer surface 90 lying flush with the outer surface of the frame member 12. In this way an auger may be employed to provide all of the necessary depressions for seating the member 20 and the flange 22 within the frame member 95 of the car and this supporting device is then secured in place by screws 25 passing through apertures formed in the flange 22.

The auger may also be employed to form a circular depression 26 in the end face of the frame member 14 which forms a part of the door 10, this recess being adapted to receive a circular plate 28 which is secured in place by screws 29. The plate 28 is formed in two parts 28^a, which are united by a U-shaped connecting bracket 30 formed by bending the sheet metal of the bracket into a substantially U-shaped form with a 100 filler plate 31 between the opposite arms. 105

The arms of the bracket are united to the plate 31 by a rivet 32. The bracket is cut away as shown at 33 and is provided with a transverse projection 34, extending parallel to the circular flange 28 and having a transverse aperture 35 in the end thereof through which a pivotal connection is formed with the complementary part of the hinge. The bracket 30 is adapted to extend between the flanges 37 of a complementary bracket 38 which seats within the cylindrical member 20. The flanges 37 are somewhat S-shaped in form and the portions 37a thereof are adapted to lie substantially flush with the outer annular surface of the circular plate 39 with which they are integrally formed. The parallel extremities of the flanges 37 are provided with apertures 40 adapted to receive a pin 41 which also engages the aperture 35 in the bracket 30 and thus connects the two brackets together. The circular plate 39 is provided with a central aperture adapted to be engaged by a screw 42 which threadedly engages an aperture 43 formed in the end wall 21 of the cup-shaped member 20. This end wall 21 is also provided on opposite sides of the screw 42 with two other apertures 44 adapted to be engaged by lugs 45 which are formed on the inner side of the circular plate 39.

In applying the hinge to the frame members 12 and 14, the flange 28 of the bracket 30 is secured to the frame member of the door with the flanges 37 of the complementary bracket secured thereto by the pin 41 and the cup-shaped member 20 with its flange 22 is separately attached to the frame member 12. The brackets of the hinge are then separated until they assume the relative positions illustrated by dotted line s in Fig. 2, after which the circular plate 39 and the flanges 37 may be passed into engagement with the cup-shaped member 20 and the screw 42 inserted to hold the members of the hinge firmly in place. The firm mounting of the cup-shaped member 20 and the flange 22 and the frame member 12 cooperates with the close fit of the flanges 37 and the plate 39 in the cup-shaped member to secure a firm support for the hinge when the parts are connected by the single screw 42 and the lugs 45 so that the swinging of the door 10 on the vertical axis of the hinge can not readily loosen any of the parts of the hinge from each other or the member 20 from the frame 12 by which it is supported. All parts of the hinge may be readily formed from sheet metal at a comparatively small cost and their novel construction enables them to be easily applied to the frame members of the automobile or to other parts with which the hinge is adapted to be used.

Although I have shown and described a single form of the hinge, for purposes of illustration, it will be understood that it may

be constructed in various other embodiments without departing from the scope of the appended claims.

I claim:

1. A hinge comprising a cylindrical member having an annular flange at one end and a transverse end wall at the other, a plate adapted to seat in said cylindrical member in contact with said end wall, means for securing said plate to said end wall, a bracket on said plate and a bracket pivotally connected to said first-mentioned bracket. 75

2. A hinge comprising a cylindrical member having an end wall, a plate adapted to seat on said end wall within said cylindrical member, said end wall having apertures therein, lugs formed on said plate to engage said apertures and pivotally connected brackets attached to said plate. 80

3. A hinge comprising a cup-shaped member having an end wall, a plate adapted to contact with said end wall within said cup-shaped member, means for securing said plate to said end wall, a pair of flanges formed integrally with said plate and a bracket pivotally mounted between said flanges, said flanges having parts adapted to engage the lateral walls of said cup-shaped member. 85 90

4. A hinge comprising a cylindrical member having a transverse flange at one end thereof, the outermost edges of said flange being concentric with said cylindrical member, a bracket having a pivotal connection with said cylindrical member, and a plate formed on said bracket, said plate having a curved outer edge. 95 100

5. A hinge comprising a cup-shaped member having a flange at its outer end, a plate adapted to seat in said cup-shaped member 105 in contact with the bottom wall thereof, a single screw for securing said plate to said bottom wall, a flange formed integrally with said plate and a bracket adapted to extend into said cup-shaped member and having a 110 pivotal connection with said flange.

6. A hinge comprising a number of semi-circular plates formed integrally with the U-shaped arms of a bracket member having a transverse extension, a second bracket member pivotally connected to said transverse extension and means for supporting said second bracket member. 115

7. A hinge comprising a cup-shaped member having a circular outer wall, a flange formed on said cup-shaped member and extending outwardly therefrom, said flange having a curved outer edge concentric with said outer wall, and a pair of pivoted brackets, one of which is secured within said 120 125 cup-shaped member.

8. A hinge comprising a cup-shaped member having a circular outer wall, an outwardly directed flange formed on said cup-shaped member, said flange having opposite paral- 130

lel edges and having opposite curved edges each connecting two ends of said opposite parallel edges, said curved edges being concentric with said outer wall, and a pair of 5 pivoted brackets one of which is secured within said cup-shaped member.

9. In combination a supporting member having a cylindrical recess formed therein, a cylindrical cup-shaped member fitting within said cylindrical recess and having an outwardly directed flange at the outer end thereof, said flange having a curved outer edge concentric with the wall of said recess, said supporting member being undercut at the outer end of said recess to receive said flange, a plate located entirely within and secured to said cup-shaped member, a bracket carried by said plate, and a second bracket pivoted on said first named bracket.

10 15 20 10. A hinge comprising a cylindrical cup-

shaped member having an end wall, a plate seated on said end wall and having integral flanges formed thereon provided with parallel extensions, means for securing said plate to said end wall, and a bracket pivoted between said parallel extensions.

11. A hinge comprising a cylindrical cup-shaped member having an end wall, a plate seated on said end wall and having integral flanges formed thereon provided with parallel extensions, means for securing said plate to said end wall, and a bracket pivoted between said parallel extensions, said bracket being formed as an integral construction comprising parallel members extending between said extensions with semi-circular flanges formed on the outer ends of said parallel members.

CARL ERIC ANDERSON.
